UNITED STATES PATENT OFFICE.

WALTER MAECHLER, OF CHICAGO, ILLINOIS, ASSIGNOR TO FRIGID FLUID COMPANY, OF CHICAGO, ILLINOIS, A CORPORATION OF ILLINOIS.

CASKET-LOWERING DEVICE.

1,402,781.

Specification of Letters Patent. Patented Jan. 10, 1922.

Application filed April 30, 1920. Serial No. 377,918.

To all whom it may concern:

Be it known that I, WALTER MAECHLER, a citizen of the United States, residing at Chicago, in the county of Cook and State of Illinois, have invented certain new and useful Improvements in Casket-Lowering Devices, of which the following is a specification.

The present invention has to do with improvements in casket lowering devices. These casket lowering devices are used for controlling the operations of lowering the caskets into the opened graves. Certain features of the invention have to do with the construction of casket lowering devices in which a framework is set onto the surface of the ground around the grave opening, the said framework being provided with suitable controlling devices whereby the rapidity of descent of the casket may be controlled. Certain of the features of the invention concern themselves particularly with the construction of the controlling device whereby the descent of the casket is regulated. In this connection one of the objects is to provide an arrangement such that the rapidity of the descent may be made practically the same regardless of the weight of the casket. Another object in this connection is to provide a very strong and rigid construction of controlling devices so that the danger of breakage in service will be reduced to a minimum.

Another object of the invention is to so construct the controlling devices that a very easy and regular operation of the same will be ensured so as to make the descent of the casket as easy and regular as possible.

Another feature of the invention concerns itself particularly with the construction and arrangement of the parts such as to very effectually prevent the entrance of sand or other foreign matter into the working parts and bearings, and the desirability of such an arrangement will be more readily understood when it is remembered that these devices are placed on the surface of the soil and must be used in all kinds of weather and under many different conditions of the elements.

In connection with the foregoing another feature of the invention concerns itself with the protection of the framework of the machine from the entrance of dirt and dust and other foreign matter. In this connec-

tion it may be stated that it is common practice to so design and construct the framework as to make it possible to lengthen or shorten the side bars according to the size of the grave opening and also according to the location of convenient and satisfactory points of support for the frame. One of the objects of the invention in this connection is to protect the joints of the framework itself against the entrance of dust and dirt and other foreign matter; and generally in this connection to protect all of the working parts of the machine in this way.

Other objects and uses of the invention will appear from a detailed description of the same which consists in the features of construction and combinations of parts hereinafter described and claimed.

In the drawings:

Figure 1 shows a plan view of a casket lowering device embodying the features of the present invention as the same might be used, the casket being shown in place on the cross straps;

Fig. 2 shows a side elevation corresponding to Fig. 1;

Fig. 3 shows a longitudinal section through one of the side rails showing how the same may be lengthened or shortened;

Fig. 4 shows an enlarged detail view of one of the locking devices by means of which the side rail sections may be joined together;

Fig. 5 shows a longitudinal section through one of the end rails showing the manner in which provision may be made for adjusting its length, and also the manner in which the rail may be protected against the entrance of dust, dirt, and other foreign matter;

Fig. 6 is a cross section taken on line 6—6 of Fig. 5, looking in the direction of the arrows;

Fig. 7 shows a cross section taken on the line 7—7 of Fig. 5, looking in the direction of the arrows;

Fig. 8 shows a plan view of the controlling head, the cover plate or cap being removed so as to show the interior construction;

Fig. 9 shows a horizontal section through the controlling head, being taken on the line 9—9 of Fig. 10, looking in the direction of the arrows;

Fig. 10 shows a vertical cross section 110

through the control head, being taken on the line 10—10 of Fig. 8, looking in the direction of the arrows;

Fig. 11 shows a detail assembly view of the centrifugal governor and its step bearing;

Fig. 12 shows a detail side elevation partly in section and on considerably enlarged scale of the top bearing and associated parts of the centrifugal governor;

Fig. 13 shows a top face view of the locking disk and flanges on reduced scale as compared to Fig. 12;

Fig. 14 shows a detail section through the step bearing at the lower end of the worm shaft; and

Fig. 15 shows a detail view of one of the dust guards for the shafts.

Referring first to Figs. 1 to 7 inclusive, I will first describe the general arrangement of the casket lowering device and will afterwards describe more in detail the construction of the control head by reference to the detailed figures illustrated in the same. The general arrangement of casket lowering device illustrated in the drawings includes four corner sections numbered 15, 16, 17, and 18, respectively; and intermediate side and end sections numbered 19, 20, 21, and 22, respectively. Between the side sections 19 and 20 there are stretched the straps or tapes 23 and 24 upon which rests the casket 25; and during the lowering operation the side sections 19 and 20 turn in reverse directions, as shown by the arrows in Fig. 1, so as to simultaneously lower both ends of each strap or tape.

One of the corner sections designated as 15 is a control section and contains the mechanism whereby the descent of the casket is controlled by controlling the rotation of the side sections 19 and 20. In this connection it is customary to extend suitable connecting devices through the end sections 22 and provide suitable gearing in the corner section 18, so that the side sections 19 and 20 will operate as a unit.

The length of the frame as a whole may be adjusted by adjusting the side sections 19 and 20 which, for this purpose, is of telescopic construction, and the width of the frame as a whole may be adjusted by adjusting the length of the end sections 21 and 22 which, for this purpose, may also be of telescopic construction. In order to facilitate packing the entire frame within a relatively small space or compass, the side sections 19 and 20 may be disconnected in their middle portions, which middle portions, however, are normally joined or coupled together by the locking devices 26 and 27. The general type of casket lowering device so far described is well known and understood in the art.

Referring now to Figs. 3 and 4, each of the side sections includes the end tubes 28 and 29

adjacent to the corresponding corner sections, and the central telescoping tubes 30 and 31 which telescope within the tubes 28 and 29. The locking devices 26 and 27 are typically shown in detail in Fig. 4. As there are shown the ends of the sections 30 and 31 are mortised or angularly cut so as to present the shoulders 32 so that a driving connection or coupling between the tubes 30 and 31 may be ensured. Reinforcing collars or bands 33 and 34 may be placed on the ends of the tubular sections 30 and 31.

The section 31 is provided on its interior with a spring latch 35, the end 36 of which is secured to the section 31, the end portion 38 of said spring latch overlapping the end of the section 30. On the end of the spring latch is a locking button 37 which, when projected, is adapted to enter the opening or recess 39 in the end of the opposite section so as to lock the two sections together. A bow spring 39 may be provided for assisting in the projection of the button into the recess.

On the section 31 to which the end 36 of the locking spring is secured, there is provided a button 40, the inner end of which engages the locking spring 35 and the outer end of which projects into a groove 41 in the operating sleeve 42. This groove 41 is eccentrically cut so that by turning the operating sleeve 42, the button 40 will be forced inwards so as to bend the same in the position shown in Fig. 4 in order to unlock the parts. Of course, a contrary movement of the ring 42 will permit the parts to be locked together. For convenience the outer surface of the ring 42 may be milled or roughened, as shown in Fig. 1.

In the end portions of the telescoping tubes 30 and 31 are the partitions 43 and 44 which are provided with angular, generally square, holes. The angular rods 45 and 46 extend through these partitions, said rods having enlarged heads 47 and 48.

In the outer ends of the tubular sections 28 and 29 are the partitions 49 and 50, through which extend the rods 45 and 46 respectively, and spring pressed buttons 51 serve to normally hold the tubes 28 and 29 in a definite position with respect to their rods 45 and 46. The inner ends of these rods are hinged or pivotally connected to shafts 52 by pivotal connections 53 as shown in detail in the left-hand side of Fig. 3. The arrangement is such that upon disconnecting the outer tubular sections 31 and 32 from each other, said sections may be telescoped into the tubular sections 28 and 29, and the sections 28 and 29 may in turn be pulled out a slight distance along the rods 45 and 46, (the spring pressed pins 51 being first disengaged by a slight extra pressure or pull) and then the telescope sections may be folded on their hinges 53 so as to make them lay parallel to the end sections 21 and 22.

It will be observed that the construction of the side sections 19 and 20 is such that sand and other foreign matter cannot gain access to their interior portions.

5. Figs. 5, 6 and 7 show in detail the construction of the end tubular sections 21 and 22. Each of these includes an inner tube 54 secured to one of the corner sections and an outer telescoping tube 55 secured to the

10 other corner section.

A tubular shaft, generally of square cross-section 56 projects out from one of the corner sections and telescopes with a rod 57 generally of square cross-section, which projects out from the corner section. This shaft and rod permit a driving connection to be established between the two corner sections. In order to prevent the parts from being disengaged more than a specified distance, 15 a tongue 58 may be struck outwardly from the tubular section 56, so as to provide a shoulder 59, and a spring pressed button 60 in the end of the rod section 57 will engage said shoulder when the specified 20 amount of extension has been reached.

Along one face of the inner tubular section 54, there is formed a series of perforations 61 which may be brought successively into alignment with a button 62 on the end of a locking handle 63. Said button is normally spring pressed inwards by a spring 64, and serves to lock the tubular sections 54 and 55 in a desired position depending upon the selected perforation 61. A 25 milled handle 65 on the pin 63 serves to facilitate the retraction of the button 62.

It will be evident that without special precaution or protection, dirt and other foreign matter might gain access to the interior 30 portions of the end sections by way of the perforations 61. This is prevented, however, by a dust guard or shield 66 which extends lengthwise of the inner tubular section 54 and covers over the various perforations 61 in a manner which will be readily evident from an examination of Figs. 5 and 7. Ordinarily these dust guards 35 may be made of thin sheet metal and riveted or pressed in place.

50. I will now explain in detail the construction of the operating head and the mode of its operation. This operating head or section is shown in detail in Figs. 8 to 14 inclusive. It was previously mentioned that 55 the shaft 52 extends to the interior of the adjacent corner section. One of these shafts extends into the control head, being the shaft shown in Figs. 8 and 9. It was also explained that the shafts 56 and 57 extend 60 to the interiors of their respective corner heads. The end portion of the shaft 57 is illustrated in Fig. 9. These shafts 52 and 57 lie at right angles to each other, and the shaft 57 preferably extends clear across 65 the operating head, finding a bearing 67 in

the side of the operating head where it enters a dead bearing 68 at the opposite side of the operating head.

The shaft 52 on the contrary stops short of the shaft 57 and finds bearing at the point 70 69 where it enters the operating head. Each of the bearings 67 and 69 includes a pair of separated bearing members with an intermediate dust or dirt-proof section 70 of leather or other suitable material. A 75 spring clip 70^a surrounds the leather or other material 70 and clamps the same against the shaft. The arrangement is such as to very effectually seclude the entrance of dust and dirt and to prevent the exit of 80 oil and other lubricant.

To the inner end of the shaft 52 is secured a bevel gear 71 which simultaneously engages bevel gears 72 and 73 on the shaft 57. The bevel pinion 73 is keyed or otherwise secured to the shaft 57, whereas the bevel pinion 72 is free to rotate on said shaft and is preferably provided with a considerable length so as to establish an effectual bearing, as shown in Fig. 9. The bevel gear and 85 pinion 71 and 73 lock the two shafts 52 and 57 together and the bevel pinion 72 rotates in harmony with both shafts.

Surrounding the bevel pinion 72 is a worm gear 74 preferably formed on a flange 90 which extends outwardly from a hub portion 75, which hub portion is secured to the bevel pinion 72 or its hub.

Adjacent to the worm gear 74 is an up-standing worm shaft 76 whose worm engages the worm gear 74. The lower end 77 of said worm shaft 76 operates in a step bearing 78. This step bearing includes an outwardly flared collar 79 resting on the balls 80 which travel in the raceway 81. 100 The upper end of the worm shaft 76 finds a bearing in a spider 82 which sets down against a shoulder 83 in the upper portion of the casing 84, as clearly shown in Fig. 10. Ordinarily this worm shaft will be ex- 105 tended on up through the spider 82 and through a bearing in the cap 85 of the shaft of the operating head, and will terminate in a squared or angular upper end 86, as clearly shown in Figs. 8 and 10. A winding key 110

or other tool may be set onto said squared head 86 for the purpose of rewinding the tapes back onto the side rails 19 and 20 after the burial operation has been completed. A leather washer or the like 87 may be placed around the upper portion of the worm shaft 76, said washer being forced up against the bottom surface of the cap 85 by a spring 88 so as to effectually exclude the entrance of dust or other foreign matter.

115 The shaft 76 carries a spiral gear 89 which is preferably located just below the position of the spider 82. This spiral gear is adapted to mesh with a spiral pinion 90 on a centrifugal governor device which I 120 125 130

will now explain in detail. This centrifugal governor device is best illustrated in Figs. 10, 11, 12, and 13. The spiral pinion 90 is secured to the upper end of a shaft 91. The lower end of this shaft rests in a step bearing 92 having a ball 93, and the upper end of the shaft, or the spiral pinion 90 itself, is provided with a socket or recess in which is ball 94. A nipple 95 is threaded through the spider 82, and has its lower end entered into the socket aforesaid and in engagement with the ball 94. The nipple 95 may be threaded up and down in the spider 82 until an exact adjustment is secured whereupon it may be locked in position by the lock nut 96.

On the shaft 91 is slidably mounted a disk 97; and a pair of plates 98 are secured to the shaft by the pin 99 so that they are compelled to rotate with the shaft. Only one of these plates appear in Fig. 11. The centrifugal weights 100 and 101 are pivoted to the end portions of the plates 98 by the pivots 102 and 103.

The under face of the plate 97 is provided on each side with a pair of downwardly depending lugs 104, well shown in Fig. 10, and the corners of the plates 105 and 106 which are pivoted to the points 102 and 103 engage the under face of the plate 97 between said lugs. In this manner the plate 97 is compelled to rotate with the shaft 91, and as the centrifugal weights 100 and 101 fly outwardly the plate 97 is raised by equal pressure on both of its sides.

A spring 107 is provided for retaining the plate 97 depressed downwardly. Above the plate 97 is a stationary plate 108 which has the upwardly extending pins 109 and 110 at two diametrically opposed points. These pins 109 and 110 have their lower ends journaled in sockets in the lugs 111 and 112 on the upper face of the plate 108, and the pins 109 and 110 are threaded in the spider 82. By turning the pins 109 and 110, the plate 108 may be adjusted up and down and may then be locked in adjusted position by the set-screws 113. In this way the idle clearance between the plates 97 and 108 may be adjusted so that the speed of the shaft 91 necessary to bring about frictional engagement may also be adjusted.

The under face or portion of the fixed plate 108 may be composed of composition material, such as raybestos or the like, which will develop the desired amount of friction while resisting heat and wear. By the use of such material, the machine may be made to operate very accurately and maintain the exact desired speed of rotation within wide ranges of casket weight.

With the construction so far described, the casket would immediately begin to descend as soon as its weight was sufficiently impressed upon the straps 23 and 24. I

have, however, provided a locking device which will serve to absolutely lock the machine until everything is in readiness for the descent of the casket, which locking device can be very easily controlled by the attendant. For this purpose, a finger 114 shown in Fig. 10 is provided on the inner end of a stub shaft which extends through the head 84, the outer end of said stub shaft having a handle 115 by which it may be rocked, said handle being clearly shown in Fig. 8. A dust washer or the like 116 serves to prevent the entrance of any dust or foreign matter into the operating head.

The finger 114 has on its end a hook which when sufficiently lowered is adapted to engage either of the studs 117 and 118 which project outwardly from the periphery of the disk 97. The hook works from above, and I have, therefore, provided on the upper face of each of the studs 117 and 118 a tapered or beveled surface, as clearly shown in Fig. 13, so that if perchance one of the studs should be directly beneath the hook when the hook is to be lowered, it would move the stop and the plate 97 a slight distance one way or the other in order to permit the hook to be completely lowered into the locking position.

I have provided a spring 119 in conjunction with this hook, said hook being so formed, as shown in Fig. 10, that it will retain the hook in either raised or lowered position according to the setting.

While I have herein shown and described only a single embodiment of the features of my invention, still I do not limit myself to the said embodiment, except as I may do so in the claims.

I claim:

1. In a casket lowering device, the combination with a pair of longitudinally extending side rails and a pair of end members at right angles thereto, the end portions of the side rails and of the end members coming together at the corners of the casket lowering device, and suitable cross straps having their end portions connected to opposite points of the side rails and adapted to wind on said side rails, of a corner head at each corner of the device, journals for the side rails and end members in said heads, suitable gearing within one of the corner heads joining together the ends of the side rail and end member which are journaled therein, and a control head at another corner of the casket lowering device, said control head including a through bearing for the end member, a dead bearing opposite to said through bearing, a shouledered beveled pinion secured to the end member adjacent to said dead bearing, a worm gear mounted on the shoulder of said pinion, another beveled pinion rotatably mounted on the end member adjacent to the

through bearing, a through bearing at right angles to the end member for the accommodation of the end portion of the side rail, a beveled gear secured to the inner end of the 5 side rail adjacent to said through bearing and meshing with both of the beveled gears aforesaid, a spider in the upper portion of the control head, a vertical worm shaft meshing with the worm gear aforesaid, a 10 step bearing for the lower end of the worm shaft, a through bearing in the spider for the worm shaft, a removable cover for the control head, a through bearing therein for the worm shaft permitting rotation of 15 the worm shaft from the outside of the control head, a dust washer on the upper end of the worm shaft adjacent to the under face of the cover plate, a spring maintaining said washer in contact with said under face, 20 a gear on the worm shaft immediately beneath the spider, a vertical governor shaft, a step bearing for the lower end thereof, a bearing recess in the upper end of the governor shaft, a ball therein, a bearing 25 stud threaded through the spider and having in its lower end a socket for engagement with said ball, means for locking said stud with respect to the spider, a friction plate located beneath the spider and sur- 30 rounding the governor shaft and having a lower friction surface, a pair of upstanding studs on said friction plate extending through the spider, means for adjusting said studs vertically with respect to the 35 spider, means for locking both of the studs with respect to the spider, a horizontal plate axially movable with respect to the governor shaft while rotatable therewith, a pair of centrifugal members pivotally 40 mounted with respect to the governor shaft and rotatable therewith, lever connections from said centrifugal members to the plate aforesaid tending to raise said plate when 45 said members are centrifugally projected, a spring on the governor plate normally de- 50 pressing said plate away from the friction plate aforesaid, a pair of outstanding peripheral stops on the movable plate, and a hook movably mounted in the control head in position to engage said stops for the purpose of arresting the rotation of the governor shaft, substantially as described.

2. In a casket lowering device, the combination with a pair of longitudinally extending side rails and a pair of end members at right angles thereto, the end portions of the side rails and of the end members coming together at the corners of the casket lowering device, and suitable cross straps 55 having their end portions connected to opposite points of the side rails and adapted to wind on said side rails, of a corner head at each corner of the device, journals for the side rails and end members in said 60 heads, suitable gearing within one of the 65 corner heads joining together the ends of the side rail and end member which are journaled therein, and a control head at another corner of the casket lowering device, said control head including a through 70 bearing for the end member, a dead bearing opposite to said through bearing, a beveled pinion secured to the end member adjacent to said dead bearing, a worm gear secured to said pinion, another beveled 75 pinion rotatably mounted on the end member adjacent to the through bearing, a through bearing at right angles to the end member for the accommodation of the end portion of the side rail, a beveled gear secured to 80 the inner end of the side rail adjacent to said through bearing and meshing with both of the beveled gears aforesaid, a spider in the upper portion of the control head, a vertical worm shaft meshing 85 with the worm gear aforesaid, a step bearing for the lower end of the worm shaft, a through bearing in the spider for the worm shaft, a removable cover for the control head, a through bearing therein for the worm 90 shaft permitting rotation of the worm shaft from the outside of the control head, a gear on the worm shaft immediately beneath the spider, a vertical governor shaft, a step bearing 95 for the lower end thereof, a friction plate located beneath the spider and surrounding the governor shaft and having a lower friction surface, a pair of upstanding studs on said friction plate extending through the spider, means for adjusting said studs vertically with respect to the 100 spider, means for locking both of the studs with respect to the spider, a horizontal plate axially movable with respect to the governor shaft while rotatable therewith, a 105 pair of centrifugal members pivotally mounted with respect to the governor shaft and rotatable therewith, lever connections from said centrifugal members to the plate aforesaid tending to raise said plate when 110 said members are centrifugally projected, a spring on the governor plate normally de- 115 pressing said plate away from the friction plate aforesaid, a pair of outstanding peripheral stops on the movable plate, and a hook movably mounted in the control head in position to engage said stops for the purpose of arresting the rotation of the governor shaft, substantially as described.

3. In a casket lowering device, the combination with a pair of longitudinally extending side rails and a pair of end members at right angles thereto, the end portions of the side rails and of the end members coming together at the corners of the casket lowering device, and suitable cross straps 120 having their end portions connected to opposite points of the side rails and adapted to wind on said side rails, of a corner head at each corner of the device, journals for the side rails and end members in said heads, suitable gearing within one of the 125 corner heads joining together the ends of the side rail and end member which are journaled therein, and a control head at another corner of the casket lowering device, said control head including a through bearing for the end member, a dead bearing opposite to said through bearing, a beveled pinion secured to the end member adjacent to said dead bearing, a worm gear secured to said pinion, another beveled pinion rotatably mounted on the end member adjacent to the through bearing, a through bearing at right angles to the end member for the accommodation of the end portion of the side rail, a beveled gear secured to the inner end of the side rail adjacent to said through bearing and meshing with both of the beveled gears aforesaid, a spider in the upper portion of the control head, a vertical worm shaft meshing with the worm gear aforesaid, a step bearing for the lower end of the worm shaft, a through bearing in the spider for the worm shaft, a removable cover for the control head, a through bearing therein for the worm shaft permitting rotation of the worm shaft from the outside of the control head, a gear on the worm shaft immediately beneath the spider, a vertical governor shaft, a step bearing for the lower end thereof, a friction plate located beneath the spider and surrounding the governor shaft and having a lower friction surface, a pair of upstanding studs on said friction plate extending through the spider, means for adjusting said studs vertically with respect to the spider, means for locking both of the studs with respect to the spider, a horizontal plate axially movable with respect to the governor shaft while rotatable therewith, a pair of centrifugal members pivotally mounted with respect to the governor shaft and rotatable therewith, lever connections from said centrifugal members to the plate aforesaid tending to raise said plate when said members are centrifugally projected, a spring on the governor plate normally de- pressing said plate away from the friction plate aforesaid, a pair of outstanding peripheral stops on the movable plate, and a hook movably mounted in the control head in position to engage said stops for the purpose of arresting the rotation of the governor shaft, substantially as described.

rails and end members in said heads, suitable gearing within one of the corner heads joining together the ends of the side rail and end member which are journaled therein, and 5 a control head at another corner of the casket lowering device, said control head including a through bearing for the end member, a dead bearing opposite to said through bearing, a beveled pinion secured to the end member adjacent to said dead bearing, a worm gear secured to said pinion, a through bearing at right angles to the end member for the accommodation of the end portion of the side rail, a beveled gear secured to the inner 10 end of the side rail adjacent to said through bearing and meshing with the beveled gear aforesaid, a spider in the upper portion of the control head, a vertical worm shaft meshing with the worm gear aforesaid, a through bearing in the spider for the worm shaft, a gear on the worm shaft immediately beneath the spider, a vertical governor shaft, a friction plate located beneath the spider and surrounding the governor shaft and having a lower friction surface, a pair of upstanding studs on said friction plate extending through the spider, means for adjusting said studs vertically with respect to the spider, means for 15 locking both of the studs with respect to the spider, a horizontal plate axially movable with respect to the governor shaft while rotatable therewith, a centrifugal member pivotally mounted with respect to the governor shaft and rotatable therewith, lever connections from said centrifugal member to the plate aforesaid tending to raise said plate when said member is centrifugally projected, a spring on the governor plate normally depressing said plate away from the friction plate aforesaid, an outstanding peripheral stop on the movable plate, and a hook movably mounted in the control head 20 in position to engage said stop for the purpose of arresting the rotation of the governor shaft, substantially as described.

15 20 25 30 35 40 45 50 55 60 65

4. In a casket lowering device, the combination with a pair of longitudinally extending side rails and a pair of end members at right angles thereto, the end portions of the side rails and of the end members coming together at the corners of the casket lowering device, and suitable cross straps having their end portions connected to opposite points of the side rails and adapted to wind on said side rails, of a control head at one corner of the casket lowering device, said control head including oppositely disposed bearings for the end member, a bearing at right angles thereto for the side rail, a beveled pinion secured to the end member between the bearings thereof, a worm gear in conjunction with said pinion, a beveled gear secured to the inner end of the side rail and meshing with the beveled gear aforesaid, a vertical worm shaft meshing with the worm gear aforesaid, a gear on the worm shaft, a vertical governor shaft, a gear thereon meshing with the worm shaft, a gear, a fixed member in the upper portion of the control head, a friction plate beneath said member and surrounding the governor shaft, and having a lower friction surface, a pair of oppositely disposed upstanding studs on the friction plate engaging the fixed member, means for adjusting said studs vertically with respect to said member, a horizontal plate axially movable with respect to the governor shaft while rotatable there-

65

cured to the inner end of the side rail adjacent to said through bearing and meshing with the beveled gear aforesaid, a spider in the upper portion of the control head, a vertical worm shaft meshing with the worm gear aforesaid, a through bearing in the spider for the worm shaft, a gear on the worm shaft immediately beneath the spider, a vertical governor shaft, a friction plate located beneath the spider and surrounding the governor shaft and having a lower friction surface, a pair of upstanding studs on said friction plate extending through the spider, means for adjusting said studs vertically with respect to the spider, means for locking both of the studs with respect to the spider, a horizontal plate axially movable with respect to the governor shaft while rotatable therewith, a centrifugal member pivotally mounted with respect to the governor shaft and rotatable therewith, lever connections from said centrifugal member to the plate aforesaid tending to raise said plate when said member is centrifugally projected, a spring on the governor plate normally depressing said plate away from the friction plate aforesaid, an outstanding peripheral stop on the movable plate, and a hook movably mounted in the control head in position to engage said stop for the purpose of arresting the rotation of the governor shaft, substantially as described.

5. In a casket lowering device, the combination with a pair of longitudinally extending side rails and a pair of end members at right angles thereto, the end portions of the side rails and of the end members coming together at the corners of the casket lowering device, and suitable cross straps having their end portions connected to opposite points of the side rails and adapted to wind on said side rails, of a control head at one corner of the casket lowering device, said control head including oppositely disposed bearings for the end member, a bearing at right angles thereto for the side rail, a beveled pinion secured to the end member between the bearings thereof, a worm gear in conjunction with said pinion, a beveled gear secured to the inner end of the side rail and meshing with the beveled gear aforesaid, a vertical worm shaft meshing with the worm gear aforesaid, a gear on the worm shaft, a vertical governor shaft, a gear thereon meshing with the worm shaft, a gear, a fixed member in the upper portion of the control head, a friction plate beneath said member and surrounding the governor shaft, and having a lower friction surface, a pair of oppositely disposed upstanding studs on the friction plate engaging the fixed member, means for adjusting said studs vertically with respect to said member, a horizontal plate axially movable with respect to the governor shaft while rotatable there-

- with, a centrifugal member pivotally mounted with respect to the governor shaft and rotatable therewith, lever connections from said centrifugal member to the plate aforesaid tending to raise said plate when said member is centrifugally projected, a spring on the governor plate normally depressing said plate away from the friction plate aforesaid, an outstanding peripheral stop 10 on the movable plate, and a hook movably mounted in the control head in position to engage said stop for the purpose of arresting the rotation of the governor shaft, substantially as described.
- 15 6. In a casket lowering device, a control head including oppositely disposed bearings for an end member shaft, a bearing at right angles thereto for a side rail shaft, a beveled pinion secured to the end member shaft 20 between the bearings thereof, a worm gear in conjunction with said pinion, a beveled gear secured to the inner end of the side rail shaft and meshing with the beveled gear aforesaid, a vertical worm shaft meshing 25 with the worm gear aforesaid, a gear on the worm shaft, a vertical governor shaft, a gear thereon meshing with the worm shaft gear, a fixed member in the upper portion 30 of the control head, a friction plate beneath said member and surrounding the governor shaft, and having a lower friction surface, a pair of oppositely disposed upstanding studs on the friction plate engaging the fixed member, means for adjusting said studs vertically with respect to said member, a horizontal plate axially movable with respect to the governor shaft while rotatable therewith, a centrifugal member pivotally mounted 35 with respect to the governor shaft and rotatable therewith, and lever connections from said centrifugal member to the plate aforesaid tending to raise said plate when said member is centrifugally projected, substantially as described.
- 40 7. In a casket lowering device, a control head including oppositely disposed bearings for an end member shaft, a bearing at right 45 angles thereto for a side rail shaft, a beveled pinion secured to the end member shaft between the bearings thereof, a worm gear in conjunction with said pinion, a beveled gear secured to the inner end of the side rail shaft and meshing with the beveled gear aforesaid, a vertical worm shaft meshing with the worm gear aforesaid, a gear on the worm shaft, a vertical governor shaft, a gear thereon meshing with the worm shaft gear, a fixed member in the upper portion of the control head, a friction plate beneath said member and surrounding the governor shaft, and having a lower friction surface, a pair of oppositely disposed upstanding studs on the friction plate engaging the fixed member, means for adjusting said studs vertically with respect to said member, a horizontal plate axially movable with respect to the governor shaft while rotatable therewith, a centrifugal member pivotally mounted with respect to the governor shaft and rotatable therewith, lever connections from said centrifugal member to the plate aforesaid tending to raise said plate when said member is centrifugally projected, substantially as described.
- 50 8. In a casket lowering device, an adjustable end member comprising in combination a pair of telescoping tubular members, there being a series of perforations in one of said tubular members, a spring-pressed stud carried by the other tubular member in position to engage a selected one of said perforations, and a protecting sheet secured to the interior of the perforated tubular member, said protection sheet lying over and covering the inner ends of the perforations for the exclusion of foreign matter from the interior of said tubular member, substantially as described.
- 95 9. In a casket lowering device, an adjustable end member comprising in combination a pair of telescoping tubular members, there being a series of perforations in the innermost tubular member, a locking stud in conjunction with the outermost tubular member adapted to project into a selected one of said perforations, and a guard sheet secured to and covering over the inner ends of said perforations, substantially as described.

WALTER MAECHLER.
